UNITED STATES PATENT OFFICE.

HAROLD V. WHEATLEY, OF EDENKILLIE, STRASSBURG, SASKATCHEWAN, CANADA.

LADDER ATTACHMENT.

1,257,056.

Specification of Letters Patent.

Patented Feb. 19, 1918.

Application filed June 4, 1917. Serial No. 172,817.

To all whom it may concern:

Be it known that I, HAROLD V. WHEATLEY, a subject of the King of England, residing at Edenkillie, Strassburg, in the Province of Saskatchewan, Dominion of Canada, have invented certain new and useful Improvements in Ladder Attachments; and I do hereby declare the following to be a full, clear, and exact description of the invention, such as will enable others skilled in the art to which it appertains to make and use the same.

This invention is an improvement in ladders and has particular reference to an attachment therefor.

In carrying out the invention it is proposed to provide the ladder with a receptacle support upon which buckets of paint and the like may be placed within easy reach of a person on the ladder.

An object of the invention is to provide an improved support which may be adjusted to any height on either side of the ladder and which includes a platform also adjustable so that the same may be made to assume a horizontal position regardless of the angle of the ladder when standing against the wall of a building or other structure.

Another object is the provision of a support which may be folded to a position along the adjacent side of the ladder when not in use.

A further object is to provide a detachment of this character which is simple in construction, easy to manufacture and effective in carrying out the purpose for which it is designed.

The inventive idea involved is capable of receiving a variety of mechanical expressions, one of which, for the purpose of illustrating the invention, is shown in the accompanying drawing, wherein:—

Figure 1 is a fragmentary front elevation of a ladder showing the support attached thereto and in operative position.

Fig. 2 is a similar view illustrating the support in its inoperative or folded position.

Fig. 3 is a side elevation of the ladder showing the support in operative position.

Fig. 4 is a vertical sectional view through the support.

Fig. 5 is a detail perspective view of the lower portion of the support.

The receptacle supporting attachment which comprises the essential feature of the invention is shown in what is now believed

to be its preferred form and when in operative position it preferably extends to the side of one of the sides or standards of the ladder 10 so that it will not interfere with a person climbing up and down said ladder. The support comprises upper and lower detachable clamps 11 and 12 which may be adjusted to any desired position on a side of the ladder and secured in their adjusted positions by means of the clamp bolts 13, said clamps being connected by a stationary bracing rod 14 which extends longitudinally of and adjacent to the side of the ladder.

The frame of the support preferably comprises a vertical arm 15 adjustable relative to the rod 14 and pivotally mounted at its lower end in a U-shaped bracket 16 carried by a plate 17 secured to the top of the lower clamp 12 adjacent its outer end and having the pivot pin 18 which extends longitudinally of said clamp and of the rungs of the ladder so that the arm 15 may be caused to assume a vertical position regardless of the angle at which the ladder 10 extends. In order to maintain the arm 15 in its vertical position the same is preferably provided adjacent its upper end with a laterally extending curved brace 19 having a longitudinal slot 20 therein for receiving a bolt 21 carried by the rod 14. A wing nut 22 is threaded upon the bolt 21 and engages the brace 19 to secure the same in adjusted positions.

The lower end of the arm 18, contiguous to the bracket 16, has secured thereto a sleeve 23 having the pivot ears 24 extending therefrom. The lower end of a diagonal brace arm generally indicated by the numeral 25 is pivotally mounted between the ears 24 as indicated at 26 and the pivot extends at right angles to the pivot pin 18. The diagonal brace arm is adjustable in length and for this purpose consists of a sleeve member 27 into which is extended the lower end of a rod 28 and carried by the upper end 100 of the sleeve member 27 is a set screw 29 which engages the rod 28 to maintain the same in adjusted positions. The upper end of the rod 28 has pivoted thereto at 30 the platform 31 the inner edge of which is detachably connected to the upper end of the arm or upright 15 by means of a catch 32. The upper end of the sleeve 27 is connected to the arm 15 by means of a sectional brace 33, the sections of which are pivoted at 34 to 110 form a break joint.

It will be apparent from the foregoing

description that the ladder 10 may be placed at an angle against the wall of a building or any other structure and by swinging the arm 15 about its pivot 18 to a vertical position and then tightening the wing nut 22 the platform 31 will be adjusted to a horizontal position so that a bucket or other receptacle may be securely placed thereon. When desiring to fold the attachment, the inner edge of the platform 31 is first detached from the upper end of the arm 15 by releasing the catch 32, and the sectional brace 33 is folded after which the diagonal arm 25 may be swung to a position alongside of the arm 15 as shown in Fig. 3.

What is claimed is:—

1. The combination with a ladder, of clamps secured thereto, a brace connection between said clamps, a frame including an arm pivotally connected to one of said clamps and movable about an axis which lies in the plane of the ladder, means carried by said arm and coöperating with said brace connection for securing said arm in adjusted positions, and a platform carried by said frame.

2. The combination with a ladder, of clamps secured thereto, a brace connection between said clamps, a frame including an arm pivotally connected to one of said clamps and movable about an axis which lies in the plane of the ladder, means carried by said arm and coöperating with said brace connection for securing said arm in adjusted positions, a platform carried by said frame, and a diagonal brace arm pivotally connected at one end to said platform and at its other end to the first named arm, the latter pivot being at right angles to the pivot of said first named arm.

3. The combination with a ladder, of clamps secured thereto, a brace connection

between said clamps, a frame including an arm pivotally connected to one of said clamps and movable about an axis which lies in the plane of the ladder, means carried by said arm and coöperating with said brace connection for securing said arm in adjusted positions, a platform carried by said frame, a diagonal brace arm pivotally connected at one end to said platform and at its other end to the first named arm, the latter pivot being at right angles to the pivot of said first named arm, said diagonal arm including longitudinally adjustable sections, and a sectional brace connecting one of said sections with said first named arm.

4. The combination with a ladder, of clamps secured thereto, a brace connection between said clamps, a frame including an arm pivotally connected to one of said clamps and movable about an axis which lies in the plane of the ladder, means carried by said arm and coöperating with said brace connection for securing said arm in adjusted positions, a platform carried by said frame, a diagonal brace arm pivotally connected at one end to said platform and at its other end to the first named arm, the latter pivot being at right angles to the pivot of said first named arm, said diagonal arm including longitudinally adjustable sections, a sectional brace connecting one of said sections with said first named arm, and a catch for detachably connecting said platform to the upper end of said first named arm.

In testimony whereof, I affix my signature in the presence of two witnesses.

HAROLD V. WHEATLEY.
